DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

Continuation of application Ser. No. 415,278, Nov. 12,
1973, which is a continuation-in-part of application
Ser. No. 91,086, Nov. 9, 1970. This application Jan. 23,
1975, Ser. No. 543,603

Int. Cl. H04n 7/18
U.S. Cl. 178—6.8

14 Sheets Drawing. 37 Pages Specification

The system includes microscope 1 and fixture 2 to position type element 4, and to enable rotational movement of typehead 4 for inspection of individual characters. IBM 1441 controller 3 with associated input/output equipment is interconnected by interface 5. In conjunction with display unit 7, having reference scales, the operator positions X-Y table 20 for measurement of selected character dimensions, and depresses a pushbutton on control panel 35. This enters the measurements into the memory of the 1441 controller. The rotate position, the tilt position, and the part number are also read into the memory of the 1441 controller. From this information, controller 3 performs a table lookup operation to determine measurement differences, if any. After dimensions of all characters (or selected characters) on a particular type element have been checked, the output is printed by an IBM 1447 typewriter, and punched on cards by an IBM 1442 card reader punch.

DEFINITION OF PARAMETERS

X_L Y_L - COORDINATES OF X-Y TABLE
WHEN Y_L PUSHBUTTON IS DEPRESSED

X_L Y_L - COORDINATES OF X-Y TABLE
WHEN PUSHBUTTON IS DEPRESSED

W/L = $-Y_L - 0.117$, C = $-X_L$

B = $Y_L - Y_L$, D = X_L
